GUTTER HANGER

Charles A. Meunier, Great Neck, N. Y.

Application April 13, 1934, Serial No. 720,361

7 Claims. (Cl. 108—29)

This invention relates to hangers for roof gutters and the invention is more particularly directed to certain improvements therein by virtue of which hangers for this purpose, which 5 while possessing the requisite strength and offering the essential resistance to bending, may be produced from a lighter gage of stock and from a considerable lesser amount of material than has hitherto been possible.

10 The invention further comprehends an improved hanger in which the suspension strap is pivotally connected with the bridge element so that the strap may be disposed in a compact folded position substantially in alignment therewith in order to occupy a minimum amount of 15 space for storage and shipment of the hangers.

15 The invention further contemplates a hanger of the indicated character, the construction and arrangement of which is such that when the hanger is in use the gutter is supported and held against outward tilting or canting.

20 Other objects in view are to provide an improved hanger for roof gutters which embodies but few and simple parts thereby rendering it 25 capable of economical production, assembly, and installation, while at the same time, providing a hanger which is highly efficient for its intended purpose.

25 With the above enumerated and other objects 30 in view, reference is now made to the following specification and accompanying drawing in which there is disclosed, by way of example, a preferred embodiment of the invention, while the appended claims are drawn so as to cover 35 variations and modifications thereof which fall within the scope of the invention.

In the drawing:

Fig. 1 is a side view of a hanger constructed 40 in accordance with the present invention and illustrating the same in applied position to a roof gutter which is shown in cross section.

Fig. 2 is a sectional plan view taken on a plane indicated by section line 2—2 in Fig. 1.

Fig. 3 is an enlarged vertical sectional view 45 taken on a plane indicated by the section line 3—3 in Fig. 1.

50 Referring to the drawing by characters of reference, A designates a standard type of roof gutter having a rolled bead B at its outer edge and an unbeaded inner edge C, while the roof D from which the gutter is supported is diagrammatically shown in broken lines in Fig. 1.

55 While the invention is disclosed in connection with that type of roof gutter hanger which includes a cradle underlying the gutter, it is to

be clearly understood that the invention is not limited thereto as the same is intended to cover any other type of hanger to which the invention is applicable.

5 The hanger embodying the present invention is formed of a flat elongated strip of copper or other suitable or equivalent material and includes a body section designated generally by the reference character E and a suspension strap broadly indicated by the reference character F.

10 The body section E in the present disclosure, includes a cradle portion or element 10 which underlies the body of the gutter A and extends from the beaded forward edge C to the un-beaded rear edge C thereof. The body section E also includes, either as an integral part of the cradle 10 or otherwise, a bridge portion or element 11 which, as shown, is joined to the cradle portion by a semi-circular bight 12 which snugly fits around the rolled bead B at the forward edge of the gutter. The opposite free end 13 of the bridge element 11 rests upon the un-beaded rear edge C of the gutter, protrudes rearwardly from beyond and is slotted as at 14 to receive therethrough the free end 15 of the cradle portion 10, which free end is of reduced width and is bent around the free end 13 of the bridge element 11 so as to secure the body E of the hanger to the roof gutter A.

15 The bridge element 11 which extends transversely of and overlies the gutter has opposite end portions 16 and 17 with the width of the material disposed horizontal, while the intermediate portion 18 is disposed vertically, this 20 being preferably accomplished by twisting the material as illustrated. Obviously by dispensing 25 the twisted intermediate portion 18 vertically the bridge element 11 possesses greater strength and resistance to the vertical supporting stresses imposed thereupon, while the entire bridge element is further strengthened 30 against bending by means of a rib 19 or bead extending longitudinally thereof and located intermediate its width. The intermediate portion 18 is further strengthened against lateral bending by the formation of a horizontal flange 35 20 extending along its lower edge.

40 The suspension strap F which is also formed of a flat elongated strip of copper or other suitable equivalent material has the width of its upper end 21 disposed in a plane coinciding with the plane of the roof D for securement thereto in flat contact therewith. The lower end 22 of the suspension strap has its width disposed in a plane 45

50 20 extending along its lower edge.

55 The suspension strap F which is also formed of a flat elongated strip of copper or other suitable equivalent material has the width of its upper end 21 disposed in a plane coinciding with the plane of the roof D for securement thereto in flat contact therewith. The lower end 22 of the suspension strap has its width disposed in a plane 55

parallel to the plane of the intermediate portion 18 of the bridge element 11 and its lower free extremity is disposed alongside of the side face of the intermediate portion 18 from which the horizontal flange 20 protrudes. This free extremity of the suspension strap is pivotally connected to the intermediate portion 18 by a pivot 23 while the free terminal is formed with an abutment 24 eccentric to the axis of the pivot 23, the extremity 10 being cut away at its forward lower corner to provide a clearance for the pivotal swinging of the strap. This permits the suspension strap to be swung from a folded compact arrangement whereby the hanger occupies a minimum space 15 for storage and transportation, to its upright supporting position. It will also be observed that due to the engagement of the eccentric abutment 24 with the flange 20 that the hanger when in use will prevent the tilting or canting of the gutter outwardly. If desired, the intermediate portion 18 may be further provided with a detent 25 such as a raised or out-pressed teat which is located, as shown, in a position to engage the forward edge of the free extremity of the lower end 20 of the suspension strap when the hanger is in use. This serves to prevent casual rearward or inward tilting of the gutter.

From the foregoing it will, therefore, be seen that a gutter hanger has been devised which is so constructed and arranged that it may be produced from a lighter gage of stock and at a considerable saving in the amount of material required than has hitherto been possible and this without reducing the strength and resistance of the elements to bending. Furthermore, the suspension strap is so associated with the bridge element of the hanger body that it may be swung on a pivot from a compact folded position for storage and transportation to an upright supporting position so as to properly support the gutter against the usual tendency to tilt outwardly.

What is claimed is:

1. In a hanger for roof gutters, a bridge element, suspension strap, a rivet permanently connecting the strap at its lower terminal to the bridge element in flat contact therewith for pivotal movement with reference thereto, and interengageable means on the bridge element and at the lower terminal of said suspension strap so constructed and arranged as to retain the gutter against movement in one direction on said pivotal connection when the strap is in upright relation with the bridge element.

2. In a hanger for a roof gutter, a bridge element having a flange at its lower edge and a suspension strap having pivotal connection with the bridge element to swing in one direction from a substantially aligned compact folded relation 60 with the bridge element, to an upright supporting relation thereto, said suspension strap having at its lower terminal an abutment eccentric to the axis of the pivotal connection for engaging with the flange to retain the bridge element and gutter against outward tilting movement when the hanger is in use.

3. In a hanger for a roof gutter, a bridge element constructed of flat elongated strip material including an intermediate portion having its width disposed in a vertical plane and having a horizontal flange at its lower edge, and a suspension strap pivoted at its lower end on an

horizontal axis to the intermediate portion of the bridge element for disposal in a folded compact relation thereto, the lower end of said strap being so constructed and arranged as to engage with the flange to hold the bridge element and gutter against outward tilting movement on the pivotal axis when the hanger is in use with the strap disposed in upright relation to the bridge element.

4. In a hanger for a roof gutter, a bridge element having a flange at its lower edge and a suspension strap having a pivotal connection with the bridge element for disposal in a folded compact relation thereto, said strap having its lower terminal so constructed and arranged as to engage with the flange for retaining the bridge element and gutter against outward tilting movement on said pivotal connection when the hanger is in use with the strap disposed in upright relation to the bridge element.

5. In a hanger for a roof gutter, a bridge element fashioned from a flat elongated strip extending transversely of and overlying the gutter, said element including opposite end portions having their widths disposed horizontal and in flat contact with the upper edges of the gutter and a twisted intermediate portion having its width disposed vertical and having a horizontal flange at its lower edge, and a suspension strap adapted to be secured at its upper end to the roof and having a twisted lower end with its width lying in a plane parallel to the plane of the width of the intermediate portion, and a pivoted connection between the bridge element and the strap to permit of swinging of the strap in one direction from a substantially aligned relation with the bridge element to an upright relation, said suspension strap having at its lower terminal an abutment eccentric to the axis of the pivotal connection for engaging with the flange to retain the bridge element and gutter against outward tilting movement about the pivotal connection when the hanger is in use.

6. In a hanger for a roof gutter, a bridge element fashioned from a flat elongated strip extending transversely of and overlying the gutter, said element including opposite end portions having their widths disposed horizontal and in flat contact with the upper edges of the gutter and a twisted intermediate portion having its width disposed vertical and having a horizontal flange at its lower edge, and a suspension strap adapted to be secured at its upper end to the roof and having a twisted lower end with its width lying in a plane parallel to the plane of the width of the intermediate portion and pivoted thereto on a horizontal axis, said suspension strap having its lower extremity so constructed and arranged with reference to the pivotal axis as to engage with the flange for limiting relative pivotal movement in one direction between the bridge element and strap and permitting swinging of said strap in the opposite direction into a folded compact arrangement.

7. A hanger for a roof gutter including a hanger body, a suspension strap pivotally connected therewith, stop means on said strap, and a single means on the body for strengthening the same and for engaging with the stop means to hold the body and roof gutter supported thereby against tilting movement on said pivotal connection when the hanger is in use.

CHARLES A. MEUNIER.
